JOHN LESLIE ALDEN, OF LA GRANGE, ILLINOIS, ASSIGNOR, BY MESNE ASSIGNMENTS,
TO WESTERN ELECTRIC COMPANY, INCORPORATED, OF NEW YORK, N. Y., A CORPO-
RATION OF NEW YORK

CORE COVERING APPARATUS

Application filed April 24, 1929. Serial No. 357,836.

This invention relates to core covering apparatus, and more particularly to an apparatus for covering electrical conductors in strand form with wrappings of insulating material.

An object of the invention is the provision of a simple inexpensive and efficient device for applying a covering to a core in an expeditious and economical manner.

10 In accordance with one embodiment thereof, the invention contemplates the provision of a common framework upon which a plurality of unitary vertical covering assemblies may be mounted. Each of the assemblies includes a casting upon which are mounted oppositely rotating serving heads for wrapping coverings of insulating material such as silk or cotton upon a wire being drawn through the axis of rotation of the heads. The insulating material is supplied from cops thereof which are mounted one above the other and are rotated in opposite directions to wrap the coverings upon the strand. Individual electrical motors are provided for 20 driving the heads of each unit through vertical shafts and gears, and each of the units has a capstan mounted intermediate the top and bottom thereof for drawing the strand through the machine and comprising a flat plate with which may be selectively associated interchangeable disks of various diameters, each of the disks having a frusto-conical face which cooperates with the flat plate to grip the wire, the interchangeable disks 30 providing means for drawing the strand through the machine at desired speeds. Each of the rotatable serving heads is provided with a cop support having knurled surfaces for retaining the paper core of the cop thereon, and an adjustable friction member is provided for varying the tension between the winding head and the cop support. A nose piece having a tapered end is provided for association with a tapered bore in the spindle to permit an easy insertion therein and removal therefrom. The driving motor transmits power to the head by means of a belt, and is hingedly mounted so that the tension in the belt may be readily regulated. 40 The insulated wire is directed by an indi-

vidual distributor to an individual take-up spool also driven by the unit motor.

Other objects and advantages of this invention will become apparent from the following detail description of one embodiment 55 thereof when considered in conjunction with the accompanying drawings, wherein

Fig. 1 is a fragmentary front elevational view of an apparatus embodying the features of this invention;

Fig. 2 is a sectional view taken on the line 2—2 of Fig. 1 in the direction of the arrows;

Fig. 3 is an enlarged sectional view of one of the serving heads also taken on the line 2—2 of Fig. 1 in the direction of the arrows: 65

Fig. 4 is an enlarged sectional view taken on the line 4—4 of Fig. 3 in the direction of the arrows:

Fig. 5 is an enlarged sectional view taken on the line 5—5 of Fig. 2 in the direction of 70 the arrows; and

Fig. 6 is a fragmentary elevational view of a portion of the structure shown in Fig. 3.

Referring now to the drawings wherein like reference characters designate the same parts throughout the several views, the numeral 9 designates a standard forming part of a common framework designated generally by the numeral 10 and which is composed of four standards 9, one mounted at each corner of the common framework 10. Horizontally disposed members 11, 12, 13 and 14 are mounted transversely of the front of the framework 10 and secured to the standards 9 and cross pieces 15 and 16 which are also secured to the standards 9 extend transversely of the ends of the framework. The cross pieces 15 extend beyond the standards 9 a distance sufficient to support shelves 17 upon which a plurality of supply spools 18 having a supply of bare wire wound thereon upon which a covering of textile is to be wound. The horizontally disposed members 11 and 12 support a plurality of serving units designated generally by the numeral 19. 85

To simplify the drawings, only a small fragment of the framework has been shown, the rest being broken away, but it will be understood that a plurality of serving units 100

19 are mounted transversely of the front of the framework and of the rear of the framework, and it will also be understood that the cross pieces 15 and 16 are also secured to other standards 9 not shown and that the rear side of the machine is exactly the same as the front.

The serving units or covering assemblies which are identical in every feature and only one of which will be described herein, are composed of a supporting casting 23 having housing portions 24 and 25 formed integral therewith which are joined by a web portion 26. Vertically disposed in the casting 23 and extending from the top to the bottom thereof is a rotatable shaft 27 journalled in suitably enclosed ball bearings 28 and 29 mounted in the top and bottom respectively of the casting. The lower end of the shaft 27 has a belt pulley 30 pinned thereto at 31 which may be driven by a belt 32 actuated by a driving pulley 33 of a suitable electrical motor 34.

The motor 34 is supported by a horizontally disposed member 35 which extends transversely of the front of the framework and which is secured at both ends to the standards 9. The motor 34 is not directly attached to the horizontally disposed member 35, but rather is mounted on a leaf 36 of a hinge 37, the other leaf 38 of which is secured to the horizontally disposed member 35. The motor may thus be moved toward and away from the shaft 27 to adjust the tension on the belt 32. A member 42 rigidly secured to the leaf 38 and threaded at its right end (Fig. 2) extends through a slot 44 in the leaf 36 and has a wing nut 45 threaded thereon to permit adjustment of the hinge to move the motor toward or away from the shaft 27, a spring 46 being interposed between the leaves of the hinge 37 to normally urge the leaf 36 away from the leaf 38. Electrical energy is supplied to the motor 34 through electrical conductors designated generally by the numeral 47 which terminate in a control switch 48 of any well known type connected to a source of electrical energy by conductors not shown.

The shaft 27 has pinned thereto spur gears 49 and 50 and a worm 51, the function of which will become apparent as the description progresses. The gear 49 meshes with a pinion 52 keyed to a hollow spindle 53 which is journalled in bearing races 54 and 55 mounted in a tubular member 56 secured to the housing portion 24 of the supporting casting 23.

Secured to the upper end of the hollow spindle 53 is a supporting head 60 which carries adjacent its outer edges a pair of textile guides 61 and 62 and which has a cylindrical recess 63 formed therein. A cop supporting member 64 is rotatably positioned in the recess 63 of the supporting head 60 by means

of a pin 65, a pointed portion 66 of which engages an annular depression 67 formed in the lower end of the supporting member 64. The pin 65 may be positioned accurately with respect to the supporting member 64 by means of a threaded member 68 which is locked in position by a second threaded member 69 having a hexagonal depression 150 in the head thereof.

A cylindrical member 70 of felt or like material is mounted in an aperture 71 formed in the supporting head 60 for connecting the supporting head to the cop supporting member. The friction member 70 is resiliently positioned in the aperture 71 by a spring 72 positioned between the friction member 70 and a threaded member 73 having a slotted head, threaded in the aperture 71. The cop supporting member 64 has on the periphery thereof three extending knurled surfaces 74 adapted to be engaged by the paper core 75 of a cop of textile 76 and retain it in position.

The spindle 53 is provided with an upper portion 77 of reduced diameter upon which the cop supporting member 64 is rotatably mounted, being secured in place as described hereinbefore. The upper end of the portion 77 of the spindle 53 has the bore thereof, tapered as shown at 78 to receive and frictionally engage a nose piece 79 having a tapered shank 80 and a serving nose portion 81. An annular member 82 having a tapered aperture therethrough is frictionally secured to the shank 80 of the nose piece and carries a textile directing member 83 for directing the textile from the guide 61 to the serving nose 79 of the serving head. The serving member 79 is provided with a usual V-shaped slot to permit the passage of wire from the spindle therethrough.

The upper housing portion 25 is somewhat similar to the lower housing portion 24 and has mounted therein a tubular member 84, carrying bearing braces 85 and 86 in which is rotatably journalled a spindle 87 which carries a supporting head, a cop supporting member and a serving member of the same type as carried by the spindle 53. However, the spindle 87 is rotated in a direction opposite to that in which the spindle 53 is rotated, a ball bearing mounted idler gear 88 being provided between the spur gear 50 and a pinion 89 keyed to the spindle 87. The lower serving head is provided with a guard comprised of a substantially U-shaped member 90 hinged to the housing portion 24 at 91 and the upper serving head is provided with a guard composed of two L-shaped members 92 and 93. The member 92 is hinged to the housing portion 25 and the member 93 is rigidly secured thereto.

A capstan designated generally by the numeral 102 is secured to a shaft 103 journalled in the housing portion 25 and carrying a

worm wheel 104 which meshes with a worm 51 secured to the shaft 27. The capstan 102 is comprised of a flat plate 104 having an annular shoulder 105 which is pinned to the shaft 103 at 106, and a disk 107 having a beveled edge 108 formed thereon for cooperating with the flat plate 104 to grip a strand 96 and serve to draw it through the machine upon the rotation of the shaft 103. It will be apparent that the speed at which the strand is drawn through the machine may be controlled by securing a disk 107 of larger or smaller diameter to the flat plate 104.

A take-up mechanism designated generally by the numeral 95 is provided for receiving the strand 96 from the supply 18 of bare wire after the strand has passed through the spindles 53 and 87 and has been covered. An idler pulley 97 mounted on a bracket 98 secured to the shelf 17 directs the strand 96 from the supply 18 to the spindles 53 and 87 which are mounted in super-posed relation. A second idler pulley 99 is rotatably mounted on a bracket 100 secured to an irregular shaped member 101 mounted on the horizontally disposed member 13. The strand 96 is drawn from the supply 18 over idler pulleys 97 and 99 by the capstan.

The right end (Fig. 2) of the shaft 103 has a pulley 109 mounted thereon, with which the belt 110 cooperates to transmit motion to a pulley 111 mounted on the end of a shaft 112 which is journaled at 113 and 114 in the upper end of the supporting member 101. Tension on the belt 110 is maintained constant by means of an idler 115 mounted on an arm of a bell crank lever 116 which is rotatable about the shaft 112 and the other arm of which carries a weight 117.

The left end (Fig. 2) of the shaft 112 supports a take-up spool 118 which is frictionally connected thereto by a pin 119 riding in an annular depression 120 on the shaft 112 and resiliently engaging the head of the spool 118.

A distributor for distributing the strand 96 evenly upon the spool 118 is designated generally by the numeral 121. The distributor is driven from the shaft 112 by a pulley 122 pinned to the shaft 112 which cooperates with a belt 123 for transmitting motion to a pulley 124 mounted on a shaft 125 journaled in the member 101. The left end of the shaft 125 has a worm 126 formed thereon for driving a worm wheel 127 upon which a heart-shaped cam 129 is mounted. A cam lever 130 having a slot 131 in a horizontally disposed portion thereof, for engaging the covered strand, has a projection 132 thereon which engages the heart-shaped cam and causes a reciprocatory motion to be imparted to the lever 130.

It is believed that a better understanding of this invention will be had by referring to the following description of the operation

of this embodiment thereof. A spool 18 of bare wire having been positioned on the shelf 17 and the strand 96 having been threaded through the spindles 53 and 87 and over the idler pulley 99 to the capstan 102 and from the capstan to the take-up spool 95, a portion of the textile on the cops 75 is wound manually about the strand. The motor 34 may then be started by operating the switch 48 in the usual manner and assuming that proper tension has been placed on the belt 32, by means of the threaded member 42 and its associated thumb nut 45, rotative motion will be imparted to the shaft 27. In rotating, the shaft 27 will drive through the aforescribed gearing, the spindles 53 and 87 in opposite directions. The rotation of the spindles will cause the textile wound on the cops 76 to be unwound therefrom and wound about the strand 96. However, since the rotation of the shaft 27 also causes through the worm 51 and worm gear 104, the rotation of capstan 102, the strand 96 will be advanced longitudinally of the spindles and the textile will be served helically upon the advancing strand. The difference between the speed of rotation of the spindle and the speed at which the textile is withdrawn from the cop 76 may be compensated for by permitting slippage therebetween, and the amount of slippage may be regulated by the adjustment of the friction drive member 70.

A strand of wire 96 having received its covering of textile in passing through the spindles 53 and 87 is directed to the take-up spool and distributed thereon by the lever 130, the operation of which is apparent.

What is claimed is:

1. In an apparatus for applying material to a core, means for applying the material to the core, a capstan for advancing the core during the application of the material thereto including a flat plate and a removable beveled disk cooperating therewith to form a material-engaging channel, and means for driving the capstan.

2. In serving apparatus, a driving head, a supply support mounted thereon, a pair of threaded members for retaining the supply support and the driving head in association, a friction member interconnecting the supply and the driving head to transmit motion from the driving head to the supply support, and a threaded member for varying the effectiveness of the friction member, one of said pair of members being provided to prevent accidental operation of the pair of members.

3. In serving apparatus, a driving head, a supply support rotatably mounted in the driving head, a retaining member threaded in the driving head and engaging the supply support to prevent longitudinal movement thereof, a threaded protective member over-

lying the retaining member to prevent accidental operation thereof, frictional driving means connecting the supply support and the driving member, and an adjusting member threaded in the driving head and controlling the frictional driving means.

4. In an apparatus for covering a core, an integral framework having a plurality of housings in spaced relation, a common shaft extending through the housings, means for rotating the shaft, separate hollow shafts supported by and extending through each of the housings and in alignment with each other, material supplying and serving means supported by each of the separate shafts, means for drawing a core through the hollow shafts in series, and means in each housing interconnecting the common and separate shafts causing material to be served upon the core in different directions by the adjacent separate shafts.

5. In a serving apparatus, a driving head, a supply support rotatably mounted in the driving head, releasable means for preventing longitudinal movement of the supply support relative to the driving head and having a hexagonal depression therein for receiving a hexagonally shaped tool, and an adjustable frictional driving connection between the supply support and the driving head and having a slotted portion for receiving a knife edged tool, whereby the releasable means and the frictional driving connection are adjustable only by different types of tool.

In witness whereof, I hereunto subscribe my name this 20th day of April, A. D. 1929.
JOHN LESLIE ALDEN.
